UNITED STATES PATENT OFFICE.

ARCHIE LA FRENIERE, OF SEATTLE, WASHINGTON.

PROCESS AND APPARATUS FOR THE PRODUCTION OF MOTION-PICTURE FILMS.

Application filed April 27, 1922, Serial No. 557,016. Renewed November 14, 1923.

To all whom it may concern:

Be it known that ARCHIE LA FRENIERE, citizen of the United States, residing at Seattle, in the county of King and State of Washington, has invented certain new and useful Improvements in Processes and Apparatus for the Production of Motion-Picture Films, of which the following is a specification.

10 This invention relates to a process and apparatus used in the production of motion picture films, being directed particularly to providing a relief background, which is so constructed that the representation of objects to be photographed as fixtures in the particular scene may be formed on this background in such a manner as to be brought out in relief in the photograph.

Furthermore, by the process and apparatus described, pictures usually requiring an out-door setting, may be as conveniently and readily taken in the studio, without sacrificing any of the natural effects.

In the drawings:—

25 Fig. 1 is a perspective view, illustrating the method and apparatus.

Fig. 2 is a similar view, showing a slightly different arrangement of illumination.

30 Fig. 3 is a plan view, illustrating the use of a light cut-off plate.

Fig. 4 is a similar view, showing the use of the cut-off plate for a part area only of the relief plate.

Fig. 5 is an elevation of the relief plate.

35 Fig. 6 is an enlarged section of the same on line 6—6 of Fig. 5.

The process of the present invention is directed to providing what may be termed a relief plate, on which there is applied

40 plastic material, and in which material the outline of the fixed objects to be photographed is cut or formed. This outlining renders the object distinct as to form, and the clearness with which the object is sought

45 to be photographed may be determined readily by the quantity of material on the relief plate which is scraped away. For example, if clouds are to be represented and photographed, such clouds will be

50 outlined by suitable stencil or instrument work in the plastic material on the relief plate, and if these clouds are to show very distinctly in the photograph, a very considerable portion of such plastic material within the cloud outline will be scraped away.

The relief plate is lighted from the rear, that is, from the plastic material side and directly opposite the camera. The objects thus formed on the relief plate may be 60 brought to a stage of illumination that will cause them to be photographed with the desired degree of sharpness.

The process is carried out by providing a relief plate 1, preferably a rigid sheet of 65 glass, on one surface of which there is provided plastic material 2, such for example, as putty, potter's clay, or similar material. The fixed objects of the contemplated picture, as trees, clouds, sun, moon, or the like, 70 are then outlined in the plastic material 2, as for example, as indicated at 3, Fig. 6. It is understood that the plastic material may be built up at varying points on the plate to different degrees of thickness, and that any 75 part of the picture outlined may be given any degree of relief by the amount of material taken away within the outline, those portions of the picture to be brought out clearly and distinctly being scraped practically free of the plastic material. 80

In connection with the relief plate, there is provided a system of artificial lighting, indicated generally at 4 and 5, it being the intention to provide these lights for independent control as at 6 and to be portable so that any particular portion of the plate may be lighted with any degree of intensity. Sun light may of course be used in lieu of these artificial lights, the rays of sun light 90 being controlled in any desired or usual manner to be directed at will, in any degree of diffusion, or directness, on any part or parts of the plate.

The invention readily lends itself to that orifice in motion picture reproduction known as the "fadeaway." To the observer, the picture, or a portion thereof, appears to gradually become dimmer and dimmer until obliterated. With the improved relief plate, 95 an opaque cut-off 7, may be used and mounted in any way so that it may be brought toward or away from the relief plate, and the light or source of illumination 8 positioned so that the use of the cut-off will gradually 100 obliterate the light from the picture, or reversely, if desired, gradually admit the light to the picture.

In Fig. 4, a cut-off 9 is shown for a particular portion of the picture on the relief 110 plate, as for example, corresponding to the representation of the moon, indicated at 10.

By the use of this cut-off, the rays of light 8 may be gradually admitted or gradually cut off from the outline of the moon on the relief plate, and hence in the reproduction, 5 the moon will appear to gradually increase or decrease in light effect.

The camera 11 is arranged on the plain side of the relief plate, that is, the side opposite the plastic material, the picture being 10 taken in the usual manner, including of course any animate objects that may be necessary in the picture.

Claims:

1. The herein described process, consisting in providing a relief plate, having a plastic material side, outlining inanimate objects in said material, lighting the plate from the material side, and photographing the plate from the plain side.

2. The herein described process, consisting in providing a relief plate, having a plastic material side, outlining inanimate objects in said material, providing the desired relief for said objects by controlling the depth to which the material is cut away, 20 lighting the plate from the material side, and photographing the plate from the plain side.

3. In combination, a relief plate having plastic material on one side to permit the outlining of inanimate objects therein, means for lighting said plate from the plastic material side, and a baffle plate for said plastic material side to govern the volume of light rays passing through the outlined objects in 30 said plastic material.

In testimony whereof I affix my signature.
ARCHIE LA FRENIERE.
